DESIGN FOR AN IDENTIFICATION BRACELET LOCKET

Julius Blumstein, Brighton Beach, N. Y.

Application November 17, 1942, Serial No. 108,799

Term of patent 3½ years

To all whom it may concern:

Be it known that I, Julius Blumstein, a citizen of the United States, residing at Brighton Beach, in the county of Kings and State of New York, have invented a new, original, and ornamental Design for an Identification Bracelet Locket, of which the following is a specification, reference being had to the accompanying drawing, forming part thereof.

I claim:

The ornamental design for an identification bracelet locket, as shown.

JULIUS BLUMSTEIN.
